CLAIM

We claim the ornamental design for a folding handle and operator cover, as shown and described.

DESCRIPTION

FIG. 1 is a front perspective view of a folding handle and operator cover showing our new design, with the folding handle in a folded position and, for context, depicted in position on a window sill;

FIG. 2 is an elevation view of a first end of the folding handle and operator cover depicted in FIG. 1;

FIG. 3 is an elevation view of the opposing end of the folding handle and operator cover depicted in FIG. 1;

FIG. 4 is an elevation view of a first side of the folding handle and operator cover depicted in FIG. 1;

FIG. 5 is an elevation view of the opposing side of the folding handle and operator cover depicted in FIG. 1; and,

FIG. 6 is a plan view of the folding handle and operator cover depicted in FIG. 1 from a viewpoint perpendicular to the viewpoint of the views of FIGS. 2, 3, 4, and 5.

The broken lines shown in the drawings illustrate portions of the design and environmental structure, and form no part of the claimed design.
